UNITED STATES PATENT OFFICE.

IRVING FLORMAN, OF NEW YORK, N. Y.

DESIGN FOR A CASING FOR A TEMPERATURE-INDICATING DEVICE.

Application filed June 29, 1925. Serial No. 13,943. Term of patent 14 years.

To all whom it may concern:

Be it known that I, IRVING FLORMAN, a citizen of the United States, residing at New York, in the county of New York and State of New York, have invented a new, original, and ornamental Design for Casing for a Temperature-Indicating Device, of which the following is a specification, reference being had to the accompanying drawing, forming part thereof.

In the drawing:
Figure 1 is a front elevation; and
Fig. 2 is a side view showing my new design.

I claim:
The ornamental design for a casing for a temperature indicating device, as shown.

IRVING FLORMAN.
